UNITED STATES PATENT OFFICE.

RICHARD G. CATOR, OF PALMYRA, NEW YORK, ASSIGNOR OF ONE-HALF TO F. J. LAWLER, OF PALMYRA, NEW YORK.

AUTOMATIC WINDOW-CLOSING DEVICE.

1,396,252.

Specification of Letters Patent. Patented Nov. 8, 1921.

Application filed December 10, 1920. Serial No. 429,767.

To all whom it may concern:

Be it known that I, RICHARD G. CATOR, a citizen of the United States, residing at Palmyra, in the county of Wayne and State 5 of New York, have invented certain new and useful Improvements in Automatic Window-Closing Devices, of which the following is a specification.

The object of this invention is to provide 10 an automatically operated and time controlled mechanism which is adapted to release a previously opened window at a predetermined time and automatically close it.

This and other objects of this invention 15 will be fully illustrated in the drawing, described in the specification and pointed out in the claims at the end thereof.

In the accompanying drawing:

Figure 1 is a front elevation of a window 20 with the automatically time controlled window closing mechanism attached thereto.

Fig. 2 is an end elevation of the window and mechanism shown in Fig. 1.

Fig. 3 is a rear elevation of the alarm 25 clock and window release operated thereby, the window and window casing being partly broken away.

Fig. 4 is a detail perspective view of one 30 of the releasing dogs for releasing the windows.

In the several figures of the drawings, like reference numerals indicate like parts.

Bedrooms are ventilated during the night 35 ordinarily by leaving the windows open. In the winter when the outdoor air is cold, the rooms get cold on this account and are, therefore, cold in the morning when it is time to get up. The present invention hereinafter described, is intended to hold the 40 windows open during the night but automatically release and close them in the morning at a predetermined time, an hour or two before getting up time. This gives the room a chance to warm up.

In the drawings, reference numeral 1 indicates a lever which is mounted to swing 45 in the window casing 2. The lever 1 is bent back at the inner end to form the shaft 1^A around which the lever 1 swings. This rearwardly extending shaft 1^A which forms part 50 of the lever 1, is mounted in suitable holes in the window casing and has a pair of outwardly projecting dogs 4 and 5 formed thereon. The dogs 4 and 5 are adapted to

swing in and out of the openings 6 and 7 55 provided for this purpose in the window casing 2. When in an inoperative position, the lever 1 normally hangs straight down on the outside of the window casing or in a perpendicular position. A weight 8 which is 60 fastened to the lever 1 near the outer end thereof, is provided to hold the lever in this position. The dogs 4 and 5 carried by the pivot of the lever are held back in their respective openings 6 and 7 in the window 65 casing when the lever 1 is in this normal or vertical position. This is shown at the right in Fig. 1.

The dog 4 is hooked shaped and as it swings in and out of the opening 6 in the 70 window casing, it extends into or withdraws from the path of the pins 9 which are carried by and project out from the lower sash 10 and move up and down therewith.

The dog 5 is straight and when it swings 75 in and out of its opening 7, it projects into the path or withdraws from the path of the pins 11 which are carried by and project out from the upper sash 12 and move up and 80 down therewith.

At the front of the window casing near the outer edge thereof is fastened the locking latch 13. The outwardly projecting end of this latch is bifurcated to form a long and a short prong 14 and 15 thereon. The 85 short prong 14 is provided at the bottom and the longer prong 15 is formed at the top of the locking latch. The lever 1 is adapted to swing up against the locking latch 13 so that it can be forced over the short prong 14 90 into the bifurcation in the locking latch where it is held in place in a horizontal position. When in this position the locking dogs 4 and 5 are held to project into the path of the pins 9 and 11 of the upper and 95 lower half of the window.

In order to lock the upper or lower or both sashes in an open position the window sashes are moved to the desired position and are held there until the lever 1 is moved 100 from its vertical position to the horizontal position as above pointed out. The sashes are then released and the counter weight 16 which is connected to the upper sash draws the sash up to the point where one of the 105 pins 11 in the sash 12 encounters the dog 5 which is held by the lever 1 to project into the path of the pins 11. This arrests the

movement of the sash and prevents the closing thereof. In this way the sashes are held open.

The counter weight 16, of which one is 5 mounted in each side of the window casing 2 and connected with a cord to the upper corners of the upper sash, is made to overbalance the weight of the upper sash so that when the upper sash is released the counter 10 weight 16 operates to raise the upper sash and close it.

The same is true of the lower sash except that in this case the sash is made heavier than the counter weights 17 which are connected to it by the cords 18^a. Thus, when 15 the lower sash is released after being opened, the weight of the sash will overbalance the counter weights 17 so that the lower sash will drop and close itself on the release 20 thereof.

In order to release the windows automatically and at a predetermined time an alarm clock 18 is used. This clock is mounted on a bracket 19, fastened to one side of the 25 window casing, with the dial facing the inside of the room and the winding mechanism facing the wall. The alarm clock is provided with the winding lever 20 for winding up the clock work and the winding 30 lever 21 for winding up the alarm mechanism. Besides these levers for winding up the clock work and the alarm, the clock is provided with the usual knurled handles 22 and 23 for moving the hands of the clock 35 and alarm, respectively. As above described, the upper and lower sashes are opened manually but are held in their opened position by the dogs controlled by the lever 1. The lever 1 in turn is held in the horizontal 40 position, in which the dogs operate to hold the window open by the locking latch 13. The end of the lever 1 is slightly curved rearwardly and extends to the rear of the alarm clock 18 and into the path of the 45 alarm lever 21. When the alarm goes off, the lever 21 rotates as the mechanism of the alarm unwinds and during the first one of the revolutions of the lever 21, the curved end of the lever 1 is slightly forced outwardly by the lever 21 so that the lever 1 is 50 forced out of engagement with the bifurcated end of the locking latch 13. The weight 8 then drops and operates to move the released lever 1 from the horizontal 55 position into a vertical position and in so doing moves the dogs 4 and 5 away from the pins 9 and 11 on the sashes. The sashes are then free to close and do so by reason of the over and under balanced weights that 60 are attached to the sash as above pointed out.

The alarm clock may thus be set to go off in the morning at a predetermined time and the windows which are held open during 65 the night will be closed at that time so that

the room can be warmed up before it is time to rise.

The alarm clock used for this purpose need not be provided with a bell alarm so that the sleeper will not be awakened at the 70 time the alarm goes off to close the window. In order to muffle the sound of the closing windows, each sash is provided with a shock absorber 24 and 25. These shock absorbers comprise spring pressed pins which are fastened into the top and bottom railing of the upper and lower sash, respectively. When the windows close, these pins cushion the contact of the sash with the window casing and in so doing prevent a loud impact 80 between the windows and the window casing.

As shown in Fig. 1, each window may be provided with a pair of the levers 1 and its associated parts. One of each of these levers is mounted at each side of the window 85 casing. In this way, the alarm clock for operating the releasing mechanism may be mounted on either side of the window. This makes it possible to install the window release on windows on which either one side 90 or the other of the window casing is obstructed so that the alarm clock cannot be mounted on the casing on that side.

I claim:

1. In an automatic window closing device, 95 the combination of a window casing, a window mounted to slide in said window casing, a lever mounted to swing at one side of said window casing, a weight carried by said lever near one end thereof, a dog formed 100 on said lever at the other end thereof, a latch adapted to normally hold said weighted end of said lever in a horizontal position and a time controlled means to force said weighted end of said lever out of engagement with 105 said latch and allow said lever to swing from a horizontal to a vertical position, means carried by said window and adapted to be engaged by said dog when held in one position and be released by said dog when moved 110 into the other direction.

2. In an automatic window closing device, the combination of a window casing, an upper and a lower sash mounted to slide up and down in said window casing, said upper 115 sash and said lower sash being counter balanced to allow said sashes to close themselves automatically on the release thereof, a lever mounted to swing in said window casing, means carried by said lever to engage said window sashes, a latch on said window casing to hold said lever in a position to make said dogs engage said window sashes and hold them open, time controlled means to release said lever and with it said window 120 sashes to permit the automatic closing thereof.

3. In an automatic window closing device, the combination of a window casing, an upper and a lower window sash mounted to 130

slide up and down in said window casing, said upper and said lower sash being counter balanced to allow said sashes to automatically close themselves on the release thereof, pins carried on the outside of said sashes, a lever mounted to swing on said window casing, a dog operated by said lever, said dog being adapted to engage said pins on said sashes to hold said sashes open, a latch on said window casing, said latch being adapted to engage and hold said lever in a position to hold said dogs in engagement with said pins in said window sashes, means to disengage said lever from said latch to release said dogs from said pins and allow said windows to close.

In testimony whereof I affix my signature.

RICHARD G. CATOR.
